1 Claim. (Cl. 179—18)

1

This invention relates to improvements in the operating characteristics of electromechanical devices having a slow acting feature and, in particular, to those devices which are required to respond and hold during the passage of a train of impulses, as for example, telephone type relays of the kind used in step-by-step automatic telephone systems.

In a well-known selector circuit using this type of relay the holding function of the relay is secured by short-circuiting a secondary winding at an appropriate time. It will be shown that the maintenance of this short-circuit during energizing periods is detrimental to the subsequent holding action of the relay, and it is, therefore, an object of the invention to provide circuit means which dispense with the short-circuit during energizing periods. A further object of the invention is to provide a system whereby the holding relay will fail to hold only on energizing pulses of such short duration that they would fail to actuate associated pulse-operated mechanisms anyway. Furthermore, the normal design of the relay may now be altered to give an even greater gain in performance. It is also an object of the invention to enable a smaller nominal release lag time to be stipulated for the relay so that subsequent switching operations can be made to occur in a shorter time.

According to the main feature of the invention, it is arranged that the short circuit applied to the relay winding for the purpose of obtaining a longer release lag, is interrupted during the period of energization of the relay.

According to a second feature of the invention, the interruption of the short circuit is automatically ensured, without affecting its efficacy during the non-energization periods, by means of a series rectifier.

According to a third feature of the invention, the interruption of the short circuit is automatically ensured, without affecting its efficacy during the non-energization periods, by means of a contact, or contacts, suitably related to the main energizing contact.

A slow release feature on relays may be obtained in one of several ways. The particular method in respect of which the present invention will be described by way of example to enable it to be better understood is that which, for convenience in switching operations, employs two windings on the relay one of which is short circuited when it is desired to obtain the slow release feature while the other winding is being energized via an impulsing contact. It is a re-

2

quirement from such relays that they shall initially respond, and subsequently hold, on a train of impulses which may have become distorted in other parts of the system and which may consist of short make pulse periods alternating with relatively long break pulse periods, the make pulse period referring to that period of time the energizing circuit to the relay is closed and the break pulse period referring to that period of time the energizing circuit is opened. At a given impulse frequency, the lower the percentage of make period, basing the percentage on the total of the make time period and break time period as 100 per cent, on which the relay will hold, the greater is the efficiency of the relay for the purpose.

It is an object of the present invention to show how the efficiency of such relays may be improved substantially. The method by which it is proposed to effect this is best described by reference to a specific practical application of the type of relay under consideration as shown in the accompanying drawings of which

Fig. 1 shows only that part of the impulsive element of a type of two-motion selector, such as is at present used in step-by-step automatic telephone exchange systems, which is necessary for an explanation of the invention.

Fig. 2 shows the circuit of Fig. 1 embodying one means of putting the invention into effect.

Fig. 3 shows tracings of oscillograms relating to the operation of the circuit of Fig. 1.

Fig. 4 shows similar tracings for the circuit of Fig. 2.

Fig. 5 shows curves illustrating the improved performance of the circuit according to the invention.

Fig. 6 shows another means of putting the invention into effect.

Referring now to Fig. 1, when the selector circuit is first seized by preceding switches in the switch train, the circuit is closed to relay A over leads 100 and 101 in a manner well-known to those versed in the art. Relay A operates and closes the make-before-break springs A1. A circuit is thus closed from ground at contacts C2 of relay C, through contacts 142 and 143 of the vertical off normal springs 140, through contacts 2 and 3 of spring set A1, through the winding of relay B, resistance YA, and the vertical magnet V to battery. Relay B operates. The vertical-magnet V is pre-energized by this circuit but will not operate in series with resistance YA and relay B. Operation of relay B closes a multiple holding ground to relay B from contacts B1 and also closes the circuit to winding 111 of relay C

through contacts B2 and resistance YB. Relay C operates on the power of its winding 111 and opens the original operating circuit to relay B at contacts C2, relay B being held operated from the ground at contacts B1. Relay C closes a holding circuit to itself through contacts C4 in parallel with resistance YA and in series with the vertical magnet V and relay B from ground at contacts B1 and prepares an operating circuit for the vertical magnet V from ground at contacts B1 through contacts 1 and 3 of spring set A1 and through the winding 110 of relay C. The circuit is now in readiness for the receipt of a train of impulses produced by the alternate closing and opening of contacts 1 and 3 of spring set A1 due to impulses received by relay A from the preceding switch train.

Relay A, following the impulses received over line 108-101 in a well-known manner, causes the contact set A1 to successively release and re-operate, closing and opening contacts 1 and 3. On the first release of relay A, the contacts 1 and 3 are closed, shorting the winding of relay B. The shorting of relay B decreases the resistance in the vertical magnet circuit and the pre-energized vertical magnet V operates from ground at contacts B1 through contacts 1 and 3 of relay A and through winding 110 of relay C and resistance YA in parallel. The vertical magnet V operates to raise the shaft of the switch mechanism one step and the shaft in taking the first step causes the operation of vertical off normal springs 140 in a well-known manner. When relay A restored, it shorted relay B as previously stated thus rendering relay B slow-to-release. Relay B will not release during the period that relay A has restored and will again be fully energized when relay A reoperates on the next pulse and removes the short from relay B.

Operation of the vertical off normal springs 140 closes the ground from contacts B1 of relay B through contacts 144 and 145 to a point between winding 111 of relay C and resistance YB and battery, thus shorting winding 111 of relay C. Resistance YB prevents the ground at contacts B1 from causing a direct short of the battery. Shorting winding 111 of relay C renders relay C slow-to-release.

Relay A, on operating, removes the short from relay B by opening contacts 1 and 3 thus closing relay B in the series circuit from ground at contacts B1 to the vertical magnet V through resistance YA and winding 110 of relay C in parallel. The addition of the resistance of the winding of relay B in this circuit causes the vertical magnet V to restore. Relay C being slow-to-release because of the shorted winding 111 does not immediately release. On the second impulse relay A restores closing contacts 1 and 3 again shorting relay B and closing the ground at contacts B1 through contacts 1 and 3 through resistance YA and winding 110 of relay C in parallel to the vertical magnet V. The vertical magnet V again operates to step the switch shaft. Shorting relay B causes an increase of current to flow in winding 110 of relay C to thereby hold relay C operated, this increase of current occurring before the slow release relay C has had time to release. The above cycle of operations continues, relay A following the impulses received from the preceding switch train and in turn pulsing the vertical magnet V to cause the switch mechanism to step. After the last impulse has been received, relay A reoperates, removing the short from relay B and placing relay B in the series

circuit to the vertical magnet through resistance YA and winding 110 of relay C in parallel. The vertical magnet V restores. Slow release relay C restores after a short period of time. Relay B is held operated from the ground at contacts B1 through relay B and through resistance YA and vertical magnet V to battery. The release of relay C opens winding 110 and also closes ground at contacts C2 through contacts 141 and 142 of vertical off normal springs 140 to associate circuit members for subsequent operation not material to the invention contained herein.

It will be noticed from the above detailed circuit explanation that the release of relay C during the period when relay A was operated between impulses was sufficiently delayed by the short circuiting of its winding 111 so that relay C could be reenergized through its winding 110 when relay A released on the following impulse. Thus relay C will be held operated during the period of impulsion provided that the per cent make is sufficiently high, the make period referring to that period of time relay A is released and relay B thereby shorted, the break period being that period of time relay A is operated and relay B thereby connected in series with winding 110 of relay C.

Without the invention about to be described, it sometimes happens that distorted impulses received by relay A are such as to cause failure of relay C to hold during impulsion although the same make pulses received by the vertical magnet V are sufficiently long to permit satisfactory operation of the selector mechanism. If, at a given impulse frequency, the C relay can be made to hold on make pulses shorter than are required for correct operation of the vertical magnet V and mechanism, then the selector will be capable of response to more widely distorted impulses than at present.

In order to show how the impulse holding efficiency of a relay, such as the C relay in Fig. 1, can be improved, consider Fig. 3 comprising tracings from oscillograms of the currents i_1 and i_2 in the C relay windings 111 and 110 respectively and of the flux ϕ , measured at the pole-face of the relay. Assume that winding 111 is short circuited and that the A1 break contacts 1 and 3 are breaking and making due to the receipt of a train of impulses by relay A. When A1 contacts 1 and 3 break, the current through winding 110 of relay C falls (point r_1 in Fig. 3) and a current is induced in winding 111 in a direction tending to maintain the relay flux. This current, i_1 , decays exponentially and there is a corresponding decay of flux, but it is still of finite value when the A1 contacts 1 and 3 close and current i_2 increases in winding 110. The flux created by the current induced in winding 111 is now in a direction opposing that due to i_2 in winding 110 (point θ in Fig. 3). Thus, the resultant flux rises slowly. It will be appreciated that if the make pulse period is short, and the succeeding break pulse period long, then the flux may not attain its maximum value during the make period and hence will reach the release value of flux during the succeeding break period earlier than would have been the case had the flux risen rapidly during the make pulse period.

It is an object of the invention to eliminate the current induced in winding 111 when current is increased in winding 110 so that the flux will more quickly attain its maximum value during the make pulse periods and will, therefore, take longer to reach the release flux value during the

succeeding break pulse periods. Figs. 2 and 4 show one way in which this is accomplished by the invention by the insertion of a rectifying element, MR, in that winding, (111 in the specific example), normally short circuited to secure the slow release feature, in such a direction as to permit energisation of the relay and, at the same time, to eliminate the induced currents in that winding which would otherwise retard the flux rise. The tracings of oscillograms in Fig. 4, 10 strictly comparable with those of Fig. 3, clearly depict the substantial increase in the rate of rise of flux and the higher average value of flux obtained during impulsion caused by the application of the invention.

Another way in which this improvement may be accomplished is shown in Fig. 6 from which it will be seen that a make contact A2 of relay A is inserted in series with the winding 111 of relay C. Contact A2 closes to permit the energisation of winding 111 when relay A operates, and opens to interrupt the short circuit each time relay A releases, that is to say during each period of increasing current in the 110 winding of relay C. The short circuit therefore is not available for the circulation of currents which would otherwise be induced in the 111 winding as a result of the increasing current in the 110 winding of relay C.

Fig. 5 gives a further illustration of the effectiveness of the invention in improving the impulse holding efficiency of the type of relay described in the specific example. In this figure which depicts curves resulting from plotting impulse frequency in impulses per second against per cent make for satisfactory holding during impulsion, curve I is for the arrangement shown in Fig. 1 with a predetermined static release lag of 100 milliseconds, curve II is for an arrangement according to Fig. 2 with a static release lag of 90 milliseconds and curve III is for the same arrangement with the static release lag increased to 100 milliseconds, the static release lag referring to that period of time that it takes the relay C to release after the current through winding 110 has been reduced by closing relay B in series with the winding 110, assuming that the current is not again increased through winding 110. It can easily be seen from curves I and II that the application of the invention reduces the static release lag of the relay while at the same time considerably improving its impulse holding efficiency, especially at the higher impulse frequencies. If, now, the static release lag

of the relay incorporating the invention be adjusted to have the same static release lag as obtained without the invention, (curve III), a further increased holding efficiency occurs, notably at lower impulse frequencies.

In the specific example which has been described, application of the invention would enable increased dialling ranges between telephone exchanges to be effected.

While the invention, and one method of carrying it out, has been described with particular reference to telephone systems and circuits, it will be appreciated that it can be applied to any mechanism requiring a slow decay of flux during periods of nonenergisation, and with substantial improvement in the time taken to attain a given flux.

I claim:

In a telephone system, a driving magnet for actuating the mechanism of an automatic telephone switch, a relay having a first winding and a second winding in inductive relation to said first winding, a source of direct current, a first circuit including said driving magnet, said first winding and said source, a rectifier, a resistance, a second circuit including said second winding, said rectifier, said resistance and said source, a third circuit for short circuiting said second winding including said rectifier and excluding said resistance and said source, means for completing said second circuit to operate said relay, means for intermittently increasing the current flow in said first circuit to maintain said relay operated and to intermittently operate said driving magnet, means operated by said driving magnet on initial operation thereof to complete said third circuit, and thereby short circuit said second winding and disable said second circuit, said rectifier connected in said second and third circuits so as to prevent the induction of current in the second winding due to the increase of current in said first winding.
